UNITED STATES PATENT OFFICE.

WILLIAM SPENCER BOWEN, OF NEW YORK, N. Y.

STEAM GENERATOR.

1,415,777.

Specification of Letters Patent.

Patented May 9, 1922.

Application filed February 16, 1920. Serial No. 359,079.

To all whom it may concern:

Be it known that I, WILLIAM SPENCER BOWEN, a citizen of the United States, residing at New York, in the county of New York and State of New York, have invented new and useful Improvements in Steam Generators, of which the following is a specification.

My invention relates generally to improvements in steam generators and more specifically to generators of a type using radiant heat.

The drawing illustrates my invention somewhat diagrammatically but is sufficient to disclose the underlying principles of the invention and enable a person skilled in the art to which this invention relates to construct an operative device. In the drawings Fig. 1 shows a vertical section of an embodiment of my invention the interior cones being shown by single lines but it will be understood that the thickness of the material employed can be varied.

Fig. 2 is an elevation of the outer cone and

Fig. 3 is an elevation of the intermediate cone.

Two cones 6 are placed base to base within the water jacket or casing 16, and secured together by any suitable means such as bolts passing through flanges (not shown) on the same. The cones are indicated as made of sheet metal as iron but infusible material may also be used if deemed advisable. When the generator is in operation each of these cones is surrounded by a flame contained within the annular space between cone 6 and a similar cone 5. Cones 5 are connected directly to the fuel line 2 which may conduct either gaseous or vaporized oil fuel for use in the generator.

Air is admitted through the air pipe 3 which preferably surrounds the fuel pipe 2 and connects to the outer cones 4 so as to feed compressed air into the annular space between cones 4 and 5. The surface of cone 5 is provided with a multiplicity of perforations and the bases of the cones 4 are closed so that all air admitted to the annular space between cones 4 and 5 must pass through these perforations. In this way complete fuel and air mixture and a hot blue flame is obtained. The conical expansion of the flame has a good effect on its burning, since it slows down the initial fuel velocity so that

mixture and burning can take place more easily and evenly.

Water is fed to the water jacket by connection 17 which leads to a water pump (not shown). After circulating through the water jacket and becoming heated to a high temperature the water under high pressure is conducted by pipe 1 to the mechanical spray caps 7 which deflect it in the form of an atomized spray. It should be noted that the water spray has no direct contact with the flame and receives its heat almost solely by radiation. Also as the water is at a high temperature and pressure, its release to the pressure within the cone 6 will cause it to burst into steam.

The steam generated passes out through ports 14 formed in the cones 6 into the general receiving chamber within the casing 16. This casing is water jacketed as above described for preheating the feed water and is surrounded with asbestos (not shown) for retaining the heat.

The cones 4, 5 and 6 act upon the steam and gases of combustion to superheat them before they pass out through outlet pipe 15. At the high temperature produced, the carbon of the fuel combines not only with the oxygen of the air but also with that of the steam, thus leaving nascent hydrogen in intimate mixture with the nitrogen of the air, also incandescent. Thus the gas mixture produced contains carbon dioxide (CO_2), steam (H_2O) and ammonia (NH_3) and it will be understood that after the gases are used in doing useful work they may be separated and recovered for commercial use.

The numeral 9 designates a flange and a base bored out so as to form the cavity 11 through which all the interior apparatus can be removed. A closure plate 12 is provided which may be bolted to the plate 10.

A spark plug 18 is provided in each of the cones 5 for initiating the burning of the combustible mixture.

The walls of cones 6 being in contact with the flame become red hot. These cones being base to base, radiate their heat to each other. This radiated heat is reflected and re-reflected within the cone receiving the radiation until the heat is completely absorbed.

Having thus described my invention what I claim and desire to secure by Letters Patent is as follows:

1. A steam generator comprising a casing

provided with a water jacket, a hollow conical body within and spaced from said jacket having outlet ports therein, a source of heat within the casing and surrounding said conical body and means for introducing water from said jacket to the interior of said body in the form of a finely divided spray.

2. A steam generator comprising a casing, a pair of conical shells having a common base placed coaxially within said casing, both of said cones having apertured shells, means for introducing a water spray in the interior of said cones, means for supplying combustible mixture about the exterior of said cones and means for supplying air under pressure to said combustible mixture to support the combustion thereof, whereby the steam generated in said shells may escape through the apertures thereof and mix with the products of combustion.

3. A steam generator comprising a water jacket and a series of coaxial conical shells within said jacket having annular spaces therebetween, means for introducing water from said jacket to the inner conical shell, mechanism for mixing fuel and air in the annular space surrounding the inner shell and means for igniting said mixture whereby the burning gases envelop the inner conical shell.

4. A steam generator comprising a casing, a plurality of coaxial conical shells within said casing, means for introducing a water spray into the inner conical shell, a source of heat within said casing applied exteriorly to said inner shell for radiating heat into the latter for vaporizing the water intro-

duced therein, a base for said casing having an opening, through which the assembly of conical shells may be inserted and a removable plate for normally closing said opening.

5. A steam generator comprising a casing, a central conical shell having an aperture formed therein, means for introducing a water spray to the interior of said shell, a perforated conical shell arranged coaxially with said central shell and spaced therefrom, means for supplying combustible mixture to the space between said conical shells, and an outer conical shell for supplying air under pressure to the combustible mixture through said perforated shell.

6. A steam generator comprising a casing, an inner conical shell having a plurality of steam outlet ports, a plurality of outer conical shells arranged coaxially in spaced relation thereto, means for introducing a water spray into said inner shell, the spaces between said conical shells forming fuel and air passages, one of said outer conical shells being perforated whereby the fuel and air may mix and form a combustible mixture and means for igniting said mixture for vaporizing said water by radiation and absorption within said inner conical shell and casing.

In testimony whereof I have hereunto set my hand in presence of two subscribing witnesses.

WILLIAM SPENCER BOWEN.
